CAR DOOR HANDLE

Reginald J. Broad, 83 Live Oak St.,
Fairfax, Calif. 94930

Filed Mar. 22, 1967, Ser. No. 6,331

Term of patent 14 years

(Cl. D10—8)

FIG_2

FIG_1

FIG_3

FIG_4

FIG_5

FIG. 1 is a view in side elevation of a car door handle showing the features of my new design;

FIG. 2 is a top plan view of the same;

FIG. 3 is a bottom plan view of the same;

FIG. 4 is a left end view in elevation of the same; and

FIG. 5 is a right end view in elevation.

I claim:

The ornamental design for a car door handle, substantially as shown.
